UNITED STATES PATENT OFFICE.

HEINRICH KOPPER, OF MÜLHEIM-ON-THE-RUHR, GERMANY.

REGULATING AND REVERSING APPARATUS FOR REGENERATING GAS-FURNACES.

1,029,696.

Specification of Letters Patent. Patented June 18, 1912.

Application filed September 26, 1911. Serial No. 651,361.

To all whom it may concern:

Be it known that I, HEINRICH KOPPER, a subject of the German Emperor, residing at Mülheim-on-the-Ruhr, in the Rhine Province, Prussia, Empire of Germany, have invented certain new and useful Improvements in Regulating and Reversing Apparatus for Regenerating Gas-Furnaces, of which the following is a specification.

10 The present invention relates to a regulating and reversing apparatus for regenerating gas furnaces, whereby, in accordance with my Patent No. 956,106 of April 26, 1910, the flow of the gas to be burned and 15 the burnt gas through the apparatus is regulated by means of varying water levels in the individual chambers or compartments of said apparatus. In the present invention the level of the liquid is adjusted by means 20 of tilttable receptacles, the discharge openings of which are capable of assuming positions at different levels.

One embodiment of my invention is illustrated in the accompanying drawing, in 25 which similar reference letters denote corresponding parts and in which—

Figure 1 is a top plan view of the apparatus, the cover of the vessel being removed and the tilttable receptacles being shown 30 partly in section and Fig. 2 is a longitudinal section on line A—B of Fig. 1.

In the drawing, which forms a part of this specification, *a* denotes a prismatic or circular vessel, which by means of partitions *b*, *c*, *d*, *f*, *g*, *h* and *i* is divided into chambers 35 I, II, III, IV, V, VI, VII and VIII. The partitions *c* to *i* are perpendicular to the wall *b*, and of those the walls *d* and *h* extend from the bottom not quite to the top 40 and the walls *c*, *f*, *g* and *i* extend from the top not quite to the bottom. The part of the wall *b* situated between the walls *c* and *f* extends from the bottom to the top, while the side parts *b'*, *b''* extend from the bottom 45 not quite to the top. At the back of the vessel *a* is a chimney flue *k* and at both sides thereof are flues *l* and *m* communicating with the furnace (not shown). The gas enters into the vessel through a conduit *w* 50 by the chambers VI and VII. For the purpose of conducting the water into the individual chambers of the vessel, bent pipes *n* and *o* are provided, which at one end are fixed to the vessel and of which the pipe *n*

at the points *n'*, *n''* communicates with the 55 chambers II and VI and the pipe *o* at the points *o'*, *o''* communicates with the chambers III and VII. The water enters the pipes *n* and *o* through suitable supply pipes *n'* and *o''*. At the opposite end, the pipes *n* 60 and *o* terminate into receptacles *p* and *q*, which by means of tubular extensions are movably borne on these pipes to be capable of swinging up and down around a central 65 axis and which are separated from one another by a partition *r*. These receptacles are provided with discharge pipes *p'* and *q'* which adjust themselves according to the position of the receptacles. The pipes *p'* and *q'* lead outwardly into discharges *p''*, *q''*. 70

The tilttable receptacles are suspended from a sprocket chain *s*, or the like, which is guided over a sprocket wheel *t* and at its ends is affixed to weighted levers *u* and *v*. Concentrically with the sprocket wheel *t* is 75 arranged a bevel gear *t'* which by means of a controlling wheel *t''* carrying a smaller bevel gear can be adjusted in different positions.

In the position shown in Fig. 2, the receptacles *p* and *q* occupy their central position. Consequently, the water in all individual compartments of the vessel stands at the same level, so that the gas entering into the vessel through the gas supply pipe *w* 80 is unable to escape in any direction from the chambers VI and VII. When, for example, by the adjustment of the sprocket wheel *t*, the receptacle *p* is lowered and the receptacle *q* raised to its highest position, 85 (as indicated by dotted lines in Fig. 2), the discharge pipe *p'* is brought into an almost horizontal position, and the pipe *q'* into a position perpendicular thereto. The water flows from the receptacle *p* through the pipe *p'* to the discharge *p''*. Consequently, the chambers III, IV, VII and VIII which directly communicate with the receptacle *p* 90 also become discharged through pipe *o*, while the water in the remaining chambers 95 rises according to the level in the receptacle *q*. Thus, upon entering into the chambers VI and VII, the gas is prevented from escaping from the compartment VI, and flows from compartment VII under the wall *i* 100 into the compartment VIII, whence through the flue *l* it passes into the regenerating gas furnace. From the latter it flows through 105

the flue *m* into the compartments IV and V, and from compartment IV under the wall *f* into the compartment III whence it escapes into the atmosphere through the chimney 5 flue *k*.
 If it is desired to have the gas circulate through the regenerating furnace in reverse direction, it is only necessary to so adjust the sprocket wheel *t*, that the receptacle *p* 10 is brought into the vertical and the receptacle *q* into the horizontal position. Then the discharge pipe *q'* adopts a horizontal position, so that the receptacle *q* and simultaneously the chambers I, II, V and VI become 15 discharged through the pipe *n*. Since the inlet opening for the water in the pipe *p'* is also raised to a higher level, the water level in the receptacle *p* and consequently in the compartments III, IV, VII and VIII is 20 allowed to rise. Upon then entering the vessel through the pipe *w*, the gas, owing to the high water level, is not allowed to pass from the compartment VII to VIII, while its passage under the wall *g* from the 25 compartment VI to V and thence into the furnace flue *m* is possible. Having circulated the furnace in reverse direction, the gas passes into the flue *l* and thence into the compartment I, whence under the wall *c* it 30 escapes into the chamber II and thence into the atmosphere through the chimney *k*. The weights on the levers *u* and *v* serve to balance the masses of the receptacles *p* and *q*. Thus, for instance, when the receptacle *p* 35 is lowered from its full line position shown in Fig. 2, the equilibrium of the receptacles *p* and *q* is destroyed. The receptacle *p* has a greater turning moment than the receptacle *q*. By the lowering of the receptacle *p*, 40 the portion of the chain *s* between the latter and the sprocket wheel is extended. Since the length of the chain is always the same, it necessarily follows that the lever *u* must be displaced. This labor is accomplished at 45 the expense of the sinking receptacle, and is recuperated when the receptacle *p* is raised, as by the potential energy accumulated in the lever *u*, the labor necessary to lift the receptacle *p* is accomplished. While the 50 latter is lowered and then raised up to the central position, the lever *v* is not influenced, that is to say, remains stationary. During the reversed order of movement, *i. e.* when the receptacle *q* is lowered and subsequently 55 raised to its central position, the lever *v* serves as a counter weight, while the lever *u* remains stationary.

The walls of the several compartments in the vessel are here shown solid, although they may be made hollow to contain a cooling medium as in my patent above referred to.

Having thus described the nature of my invention, I do not wish to restrict myself to the particular construction set forth and

illustrated, as various modifications may be made by those skilled in the art without deviating from the spirit of my invention.

What I claim and desire to secure by Letters Patent is:

1. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected and tilttable receptacles, the inner spaces of which are separated from one another and have discharge openings, each of said receptacles communicating with certain of the said chambers and means for enabling the tilting of the said receptacle. 70 75 80 85

2. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected and tilttable receptacles, the inner spaces of which are separated from one another, each of said receptacles communicating with certain of the said chambers, discharge pipes leading outwardly from each of said receptacles and means for enabling the tilting of the said receptacles. 90 95 100

3. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected and tilttable receptacles, the inner spaces of which are separated from one another and have discharge openings, pipes communicating at one end with certain of the said chambers and at the other end each with one of said receptacles and means for enabling the tilting of the said receptacles. 105 110 115

4. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected and tilttable receptacles, the inner spaces of which are separated from one another, discharge pipes leading outwardly from each of said receptacles, pipes communicating at one end with certain of the said chambers and at the other end each with one of said receptacles and means for enabling the tilting of the said receptacles. 120 125 130

5. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected receptacles capable of tilting around a central axis and the inner spaces of which are separated from one another and have discharge openings, means for conductively connecting each of said receptacles with certain of the said chambers and means for enabling the tilting of the

10 spaces of which are separated from one another and have discharge openings, means for conductively connecting each of said receptacles with certain of the said chambers and means for enabling the tilting of the

15 said receptacles.

6. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected receptacles capable of tilting around a central axis and the inner spaces of which are separated from one another and have discharge openings, means for conductively connecting each of said receptacles with certain of the said chambers, and a draft mechanism connected to said receptacles for enabling the tilting of the latter.

7. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected receptacles capable of tilting around a central axis and the inner spaces of which are separated from one another and have discharge openings, means for conductively connecting each of said receptacles with certain of the said chambers, a draft member connected to said receptacles and an adjusting mechanism for said draft member to enable the tilting of the said receptacle.

8. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected receptacles capable of tilting around a central axis and the inner spaces of which are separated from one another and have discharge openings, means for conductively connecting each of said receptacles with certain of the said chambers, a counter balanced draft member connected to said receptacles and an adjusting mech-

anism for said draft member to enable the tilting of the said receptacle.

9. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected receptacles capable of tilting around a central axis and the inner spaces of which are separated from one another and have discharge openings, means for conductively connecting each of said receptacles with certain of the said chambers, a flexible member engaging said receptacles, means over which said member is guided and an adjusting mechanism for the said member to enable the tilting of the said receptacles.

10. In the herein described regulating and reversing apparatus, the combination with a vessel divided into a plurality of water-containing chambers communicating with one another partly at the top and partly at the bottom, of conduits supplying gas to and conducting it away from the said chambers, rigidly connected receptacles capable of tilting around a central axis and the inner spaces of which are separated from one another and have discharge openings, means for conductively connecting each of said receptacles with certain of the said chambers, a flexible member engaging the said receptacles, a counter balanced lever for and connected to each end of the said member, means over which said member is guided and an adjusting mechanism for the said member to enable the tilting of the said receptacles.

11. In the herein described regulating and reversing apparatus, the combination with a vessel divided into a plurality of water-containing chambers communicating with one another partly at the top and partly at the bottom, of a gas supply pipe leading into some of the chambers of the said vessel, flues for conducting the gas away from the said vessel, two rigidly connected tiltable receptacles, the inner spaces of which are separated from one another and have discharge openings, pipes which are connected each to one of said receptacles and of which one communicates with two of said chambers and the other with two other of said chambers and means for enabling the tilting of the said receptacles.

In testimony whereof I affix my signature in presence of two witnesses.

HEINRICH KOPPER.
